GAME

Arthur H. Leonard, Jr., Wellesley Hills, Mass., assignor to Milton Bradley Company, Springfield, Mass., a corporation of Massachusetts

Application April 21, 1936, Serial No. 75,535

6 Claims. (Cl. 273—40)

This invention relates to improvements in game apparatus and is directed more particularly to a novel game apparatus of the type where the winner of the game is determined by chance rather than skill of the players.

It is one of the principal objects of the invention to provide a game which involves a plurality of movable parts and which is colorful and interesting to play. The game apparatus includes a plurality of movable pieces which may be called playing men, and which are moved one at a time from their starting positions by a chance-operated actuating means and according to the invention the pieces may be owned by the various players and the player "owning" the last piece to be displaced wins the game.

It is another object of the invention to provide an apparatus including a base and a plurality of movable spheres which are initially retained in certain places relative to the base and an actuating member which is arranged to come into contact with the spheres one at a time and displace them from their said certain places.

It is another one of the objects of the invention to provide a game which is simple in form so as to be relatively inexpensive to manufacture and easy to play and which at the same time brings the element of chance into play so that the winner is readily and fairly determined.

Various other objects and advantages of the invention will become more apparent after a reading of the following description and reference will be had to the accompanying drawing, wherein:

Fig. 1 is a plan view of the apparatus of the invention;

Fig. 2 is a side elevational view of the apparatus shown in Fig. 1;

Fig. 3 is a partial side elevational view to explain certain features of construction;

Fig. 4 is a partial plan view showing a portion of the base of the apparatus to explain certain features thereof;

Fig. 5 is a sectional view on the line 5—5 of Fig. 4; and

Fig. 6 is a partial side elevational view showing a modification of the construction shown in Fig. 3.

Referring now to the drawing more in detail the invention will be fully described.

In Figs. 1 and 2 there is shown a base 2 which is preferably formed of some relatively rigid and inexpensive material, such as wood, and according to the preferred form of the invention it consists of a substantially flat and circular plate-

like member. Extending upwardly in spaced relation from the upper side of the plate 2 are a plurality of what may be called supporting or T members 4.

These members 4 are preferably formed of wood and may have their lower ends seated in suitable holes in the base. They are arranged to support on their upper ends spherical members 6 and accordingly their upper surfaces are preferably formed somewhat concave (see Fig. 3) so as to have a peripheral rim extending around a hollow 5 so that the spheres 6 may be releasably supported as will appear.

According to the form of the invention at present preferred, the members 6 are formed of some relatively light weight material, such as celluloid, and are so supported that when they are struck from the side they readily become displaced from the parts 4. They may be attached to the T's 4 as by a string or the like 8 so that when displaced they will not become too disassociated from the apparatus.

That is, a length of string 8 may have one end secured to one side of the ball 6 and its other end looped around the member 4 as shown. It will be noted that such a connection is sufficiently flexible to allow the balls to become readily displaced yet it is so arranged that the ball cannot be readily retrieved.

Then some means is provided to displace the balls and, as indicated above, this means is chance-operated. That is to say, there is preferably nothing about the construction which makes it possible to bring about the displacement of one ball more readily than the others, and I have found that during the course of many plays, there is no ball which may be said to be more easily displaced than the others.

Various arrangements may be provided for displacing the balls, but according to the preferred form of the invention, a support member 10, which is U-shaped as shown, is provided and this has its opposite ends seated in hubs 12 which are rigidly secured to the base 2. Of course, the support 10 may be seated in holes provided in the base, if desired but in any event, it is preferable that the construction be such that the apparatus may be readily disassembled so that it may be packed in convenient form.

The support 10 extends over and above the base 2 as shown in Fig. 2 and has what may be called a saddle 14 disposed centrally thereof. This saddle 14 includes spaced enlarged parts with a reduced part in between as shown.

Pivoted to the reduced part for swinging move-

ments and so as to be thereby prevented from endwise movement from off the saddle 14, is what I call an actuating or displacing unit 18. Preferably this member 18 carries a ball 16 or the like on its lower end suspended from the connection 18.

According to the preferred form of the invention, the member 18 is made from wire and in upper and lower sections. The upper end of the upper section is looped around the saddle 14 as shown and the adjacent ends of the parts of the members 20 and 22 are connected by loops 24, 26 and a ring 28. These members, as stated, are made from wire and, being connected as they are, they provide a joined rod-like member as distinguished from a more flexible member such as a cord. Were a cord employed for member 18 it would, as it swings, be likely to be wound around rod 10 but this is obviated by the use of the relatively stiff jointed member 18.

In the form shown, the members 6 are disposed in a circular arrangement adjacent the marginal edge of the circular plate 2. The connection 18 is of such construction that it is free to swing over an area of such size that it may come in contact with any and all of the balls 6. As above pointed out, the balls 6 are arranged to be readily displaced from their retaining positions when struck by another object.

It is desired to here point out that there are various ways in which the actuating or displacing function may be accomplished, it being the principal object to bring about the displacing of the balls 6 one at a time, and preferably not in any particular order, so that the ball 6 last remaining in place may be readily determined and all according to chance.

Rather than merely moving the member 16 to a raised position and then releasing it so as to allow it to swing on its pivot, I provide actuating means for propelling the ball 16 and causing it to be swung in all directions and this means takes the form of a revolving top 30 having a projection 32 and a rotatable shaft 36 and a handle part 34. The top may be wound up in various ways and, according to the invention, is allowed to spin on the base 2 in such a way that it contacts the ball 16 and causes that member to swing in all directions on its pivot.

If desired, a dish-like member 38 may be provided in the base 2, preferably in the approximate center thereof, and it is so arranged as to provide a recess 40. The top 30 may then be caused to revolve within a more or less central and restricted area bounded by the sides of the member 38 so that as the ball 16 returns to its normal position after having been propelled outwardly it again comes into contact with the top and is thereby sent outwardly to hit another ball 6.

According to one modification of the invention, the balls 6 may be retained in spaced relation on the base without the T members 4. That is to say, a base 2' may be formed to have a plurality of recesses 7 in the upper side thereof of such shape and size as to releasably hold the balls 6 as shown in Fig. 6.

It will be obvious that the balls 6 may be of various colors as well as the other parts of the apparatus and it may be pointed out that in operation the sight of the member 16 swinging crazily in all directions and knocking the colored balls 6 from off their supports is fascinating and affords great amusement.

I find that it is desirable to make each ball

or playing piece 6 distinctive in order that the players may choose one or more of them as their playing pieces and then, of course, that player whose ball remains on its support longest wins the game. This distinctiveness may be provided by giving each of the balls a distinctive color or marker or the base 2 may be marked in some way, as by placing a different number thereon adjacent each of the ball supports, as shown in Fig. 1.

While I have described the invention in great detail and with respect to a preferred form thereof, it is not desired to be limited thereto since many changes and modifications may be made therein without departing from the spirit and scope of the invention.

What it is desired to claim and secure by Letters Patent of the United States is:

1. As a new article of manufacture, a game comprising in combination, a base having retaining sockets for a plurality of balls, a support on said base, a relatively stiff, jointed actuating member including rod-like wires connected together and pivoted to said support and having a free end portion movable relative thereto for displacing said balls, and actuating means movable on said base for contacting and moving said free end portion of the movable member.

2. As a new article of manufacture, a game comprising in combination, a base provided with sockets for removably retaining a plurality of balls around a central part thereof, a plurality of balls, an actuator movable relative to said base adapted to engage any one or all of the said balls and displace them from said retaining sockets, said actuator including a plurality of relatively stiff rod-like wires connected together, means associated with said base and balls limiting movements of the balls relative to said base, and means in the central part of said base to engage said actuator.

3. As a new article of manufacture, a game comprising in combination, a base having a plurality of sockets spaced in a circle therearound, a plurality of balls for resting on said sockets, a support, a relatively stiff, jointed swingable member mounted on said support having means to engage any one or all of said balls to displace them from said sockets, and a rotatable member for engaging and swinging said swingable member.

4. As a new article of manufacture, a game comprising in combination, a base, a plurality of ball sockets spaced around a central portion of said base, a plurality of balls for resting on said sockets, a support, a relatively stiff, jointed actuator swingable in all directions on said support having a part for engaging any one or all of said balls on said sockets to displace them, a spinning member for engaging and swinging said actuator and means to retain the spinning member in the central portion of said base.

5. As a new article of manufacture, a game comprising in combination, a base, a plurality of movable members supported in sockets provided thereon, a relatively stiff, jointed swingable member including rod-like wires connected together and pivoted to said support and having means to engage any one or all of said members to displace them from position, and a rotatable member for engaging and swinging said swingable member.

6. As a new article of manufacture, a game comprising in combination, a base, a plurality of balls removably supported in sockets provided in

said base around a central portion thereof, a support extending upwardly over said base, an actuator swingable in all directions on said support having a part for engaging any one or all of said balls to displace them, said actuator including a plurality of relatively stiff rod-like

wires jointed together, a rotatable spinning member for engaging and swinging said actuator, and means for retaining the spinning member in the central portion of said base.
